UNITED STATES PATENT OFFICE.

ADOLPH WIDMER AND SAMUEL WIDMER, OF PATERSON, NEW JERSEY.

NARROW-WARE LOOM.

No. 890,320.

Specification of Letters Patent.

Patented June 9, 1908.

Application filed December 21, 1907. Serial No. 407,571.

To all whom it may concern:

Be it known that we, ADOLPH WIDMER and SAMUEL WIDMER, citizens of the United States, residing in Paterson, Passaic county, 5 New Jersey, have invented a certain new and useful Improvement in Narrow-Ware Looms; and we do hereby declare the following to be a full, clear, and exact description of the invention, such as will enable others skilled in 10 the art to which it appertains to make and use the same, reference being had to the accompanying drawings, and to the letters of reference marked thereon which form a part of this specification.

15 This invention relates to looms and particularly to ribbon looms and it has for its object to provide an improved means for operating the shuttle-driving rack, whereby to secure a smoother action of said rack and a 20 material reduction of vibration in the loom and at the same time render the parts capable of adjustment, notwithstanding such conditions as irregularities of floor surface, so as to insure their proper coöperation with each 25 other at all times.

The invention will be found fully illustrated in the accompanying drawings, wherein,

Figure 1 is a side view of so much of the 30 improved loom as involves the present invention; Fig. 2 is a plan view of substantially what is shown in Fig. 1, portions appearing in section; Fig. 3 is a vertical sectional view, slightly enlarged, taken in the 35 plane of a certain rock-shaft *r*; and, Fig. 4 is a detail of a portion of the means for effecting the movements of said rock-shaft.

In the loom frame *a* is journaled in the usual manner the crank shaft *b* carrying 40 gear wheels the nearer one of which appears in the drawings and is marked *c*. An auxiliary frame *d* projects from the side of the loom frame *a* and may be described as follows: This auxiliary frame comprises a stand 45 *e* which is arranged parallel with the side of the loom frame, the braces *f* and the brackets *g*, *g'*, *h* and *i*. The braces *f* are bolted to the frame *a* and at their outer ends are formed with vertical slots *j* through which 50 and horizontal slots *k* of the stand *e* extend the bolts *l*. The slots *j* and *k* allow a vertical and horizontal adjustment of the stand and braces relatively to each other, so that the auxiliary frame may be adapted to various 55 irregularities in the floor surface on which the loom rests.

The bracket *g* comprises a horizontal portion *m* and two downwardly extending legs *n* which are set in vertical grooves *o* in the front face of the stand *e* and are secured to 60 the latter by the bolts *p* which project through slot *q* in the stand *e* and thus permit vertical adjustment of the bracket *g*. The bracket *g'* is formed with a bearing portion *g'* 65 for a rock shaft *r* and with a depending portion *g''* which is secured by bolts *s* to the stand *e*; said bolts extend through vertical slots *g'''* in the bracket *g'* allowing vertical adjustment of said bracket.

t is a shaft which is journaled in the 70 bracket *g*, extending through a vertical slot *g⁵* in the bracket *g'*, and also journaled in a vertically adjustable bracket *u* secured to the frame *a*; this shaft carries the gear *v* which meshes with a gear *w* on shaft *b*, and also 75 a cam *x*. The horizontal portion *m* of bracket *g* carries the studs *y* which project rearwardly and carry anti-friction rollers *z*. On these rollers runs a horizontal movable rack 1 having slots 2 receiving the rollers and 80 an intermediate slot 3 through which shaft *t* projects, the studs having shoulders 4 and washers 5 which insure a true parallel movement of the rack with respect to the side of the loom frame. The rack carries the rear- 85 wardly projecting studs 6 on which are arranged anti-friction rollers 7 receiving between them, and bearing against the periphery of the cam *x*. The rack meshes with a pinion 8 on the rock shaft *r*, the latter also 90 carrying a two-armed crank 9, which crank and the pinion hold said rock-shaft against longitudinal movements in its bearing. The batten, marked 10, is carried by the lay- 95 swords 11 arranged on the shaft 12 rocking in the frame *a* and bracket *i*.

13 designates the rack arranged on the batten and adapted to actuate the shuttles 14 by the means and in the manner well known. The bracket *i* is fork-shaped and is 100 attached to the stand *e* by the bolt 15 arranged in the slot 16 of the stand so that the bracket is adjustable. The bracket *h* is arranged in the horizontal groove 17 in the face of the stand *e* and is secured to the latter by the bolt 18, which passes through a horizontal slot 19 in the bracket. The brackets *h* and *i* carry the pairs of pulleys 20, the pulleys on bracket *h* being arranged on a stud 21 which is vertically adjustable 105 in a slot 22 in said bracket. Over the pulleys 20 on bracket *h* and under the pulleys on

bracket *i* extend the straps 23, the same being attached to the rack 13; one of these passes over a pulley 24 carried at the near end of the batten and the other passes over 5 a pulley 25 at the far end of the batten. These straps are connected to the hooks 26 of the couplings 27 pivoted on the studs 28 arranged in radial slots 29 in the arms of the crank 9.

- 10 On a stub shaft 30 projecting from the frame *a* are journaled the fast and loose pulleys 31 and 32, 33 being a gear which rotates with pulley 31 and meshes with gear *c*. The power is taken into the loom by means of a 15 belt which may be shifted from one of the pulleys 31 and 32 to the other by a belt shifter 34 carried by a rock shaft 35 journaled in bearings 36 in the braces *f* and carrying an operating handle 37. 38 designates 20 one of the pitmen connecting the batten with the gear *c*, whereby the batten is oscillated from shaft *b*.

The operation of the loom is as follows: When the pulley 31 is rotated, it operates, 25 through gears 33, *c*, *w* and *v* to rotate shaft *t* and consequently the cam *x*. Said cam thus reciprocates the rack 1 which acts through pinion 8 to rock rock-shaft *r* and thus oscillate the crank 9. The crank, to which the 30 straps 23 are connected in the manner already described at opposite sides of its fulcrum, thus pulls on one strap while it gives way on the other, thereby reciprocating the rack. At the same time the batten is being reciprocated through the pitman 38. In order to 35 secure the equalized movements of the rack in each direction, the pulleys 20 on bracket *h* may be adjusted vertically so as to bring them in the same horizontal plane in which, 40 in the setting up of the loom, shaft *t* may come, the studs 28 being of course adjusted

with the same purpose in view. Likewise, other parts of the auxiliary frame *d* may be adjusted with reference to each other so as to secure the proper coöperation of the parts 45 and adapt the mechanism to various irregularities in the floor surface and other conditions which may be met with.

Having thus fully described our invention, what we claim and desire to secure by Let- 50 ters Patent is:

1. In a narrow-ware loom, the combination of the frame, the lay or batten structure, the shuttle-driving rack arranged in said lay structure, a rocking structure fulcrumed between its ends, the crank - shaft, gearing, comprising a rack and pinion, connecting said rocking structure with the crank shaft, and flexible connections connecting said rocking structure with the shuttle driving 60 rack, substantially as described.

2. In a narrow-ware loom, the combination of the frame, the lay or batten structure, the shuttle-driving rack arranged in said lay structure, a rocking structure, the crank- 65 shaft, means for transmitting the power from the crank shaft to said rocking structure comprising a rotary shaft, a cam on said rotary shaft, a rack controlled by the cam and a pinion engaging the rack and carried by 70 said rocking structure, and flexible connections connecting said rocking structure with the shuttle-driving rack, substantially as described.

In testimony that we claim the foregoing 75 we have hereunto set our hands this 13th day of December, 1907.

ADOLPH WIDMER.
SAMUEL WIDMER.
